UNITED STATES PATENT OFFICE

115,640

DESIGN FOR AN OIL BURNER

Reginald W. Beckett, Elyria, Ohio

Application February 4, 1938, Serial No. 74,886

Term of patent 14 years

To all whom it may concern:

Be it known that I, Reginald W. Beckett, a citizen of Canada, residing at Elyria, in the county of Lorain and State of Ohio, have invented a new, original, and ornamental Design for Oil Burners, of which the following is a specification, reference being had to the accompanying drawings, forming part thereof, in which:

Figure 1 is a perspective view of an oil burner embodying my new design, taken from a position rearwardly and to one side thereof;

Figure 2 is a perspective view of the burner, taken from a position forwardly and to one side thereof;

Figure 3 is a plan view of the burner; and

Figure 4 is a front elevational view of the burner.

The dominant features of my design reside in the portions shown in full lines.

I claim:

The ornamental design for an oil burner, substantially as shown and described.

REGINALD W. BECKETT.
